US0D1060739S

(12) **United States Design Patent** (10) Patent No.: **US D1,060,739 S**
(45) Date of Patent: ** Feb. 4, 2025

(54) **CONSTRUCTION JOINT MATERIAL WITH ADHESIVE**

(71) Applicants: **Tomoegawa Co., Ltd.**, Tokyo (JP); **Yoshino Gypsum Co., Ltd.**, Tokyo (JP)

(72) Inventors: **Tomoki Furue**, Shizuoka (JP); **Kiyoshi Hosoi**, Shizuoka (JP); **Yuuya Ishizaka**, Shizuoka (JP); **Wataru Ohuchi**, Tokyo (JP); **Takuji Yamashita**, Tokyo (JP); **Shun Tsukamoto**, Tokyo (JP)

(73) Assignees: **TOMOEGAWA CO., LTD.**, Tokyo (JP); **YOSHINO GYPSUM CO., LTD.**, Tokyo (JP)

(**) Term: **15 Years**

(21) Appl. No.: **35/516,750**

(22) Filed: **Mar. 25, 2022**

(80) **Hague Agreement Data**

Int. Filing Date: **Mar. 25, 2022**

Int. Reg. No.: **DM/221864**

Int. Reg. Date: **Mar. 25, 2022**

Int. Reg. Pub. Date: **Mar. 31, 2023**

(30) **Foreign Application Priority Data**

Oct. 13, 2021 (JP) ..... 2021-022285 D

(57) **CLAIM**

The ornamental design for construction joint material with adhesive as shown and described.

DESCRIPTION

1. Construction joint material with adhesive

1.1 : Perspective

1.2 : Front

1.3 : Back

1.4 : Left

1.5 : Right

1.6 : Top

1.7 : Bottom

1.8 : Enlarged cross-section

The article is a construction joint material with adhesive, which is mainly used for filling gaps between wall ends and ceilings, etc. in construction; reproduction 1.8 is an enlarged

(Continued)

cross-sectional view taken along the line A-A in reproduction 1.2; the broken lines shown in the reproductions illustrate portions of the construction joint material with adhesive that form no part of the claimed design; the dash-dotted lines indicate the boundary of the claimed design; the dash-dot-dot-dash lines indicate a symbolic break. The break lines, as well as any portion of the article between the break lines, form not part of the claimed design.

1 Claim, 8 Drawing Sheets
